UNITED STATES PATENT OFFICE.

CHARLES W. McCORMICK, OF EMPORIA, KANSAS, ASSIGNOR TO LAMSON CONSOLIDATED STORE SERVICE COMPANY, OF NEWARK, NEW JERSEY, A CORPORATION OF NEW JERSEY.

STORE-SERVICE APPARATUS.

No. 896,747.

Specification of Letters Patent.

Patented Aug. 25, 1908.

Application filed February 20, 1905. Serial No. 246,402.

To all whom it may concern:

Be it known that I, CHARLES W. McCORMICK, of Emporia, in the county of Lyon and State of Kansas, have invented certain new 5 and useful Improvements in Store-Service Apparatus, of which the following is a specification.

My invention relates to improvements in cash and package carriers and to that class in 10 which a suitable basket or receptacle is detachably connected to a carrier adapted to run upon a suspended wire.

One object of the invention is to provide 15 automatic mechanism for locking the basket to and releasing it from the carrier.

Another object is to provide improved propelling mechanism for despatching the carrier.

These and other objects are accomplished 20 by the mechanism hereinafter particularly described.

In the accompanying drawings which illustrate a construction embodying my invention, Figure 1 is a side elevation of a cash 25 and package carrier embodying the features of my invention, and showing a carrier at the salesman's station. Fig. 2 is a similar view from the opposite side showing the carrier at the cashier's desk or elevated station. Fig. 3 is an enlarged detail view of part of the carrier frame showing the lock by which the basket is held to the carrier and other details 30 hereinafter described. Fig. 4 is a similar view to Fig. 3 showing the lock on the carrier 35 before the basket is raised for engagement. Fig. 5 is an end view partly in section and showing the lock in a similar position to that shown in Fig. 3, in which the basket is locked to the carrier. Fig. 6 is a side elevation of 40 the carrier with the upper part of the basket shown locked to the carrier. Fig. 7 is a top plan view of the basket plate which is adapted 45 to be locked to the carrier and released therefrom. Fig. 8 is a perspective view of the lock on the carrier which engages the basket and locks same to the carrier. Fig. 9 is a side view of the stirrup forming part of 50 the elevating mechanism. Fig. 10 is an end view of same. Fig. 11 is an end view looking 55 at the plate which is to be locked to or unlocked from the carrier. Fig. 12 is a side elevation with part of the frame of the carrier removed showing yielding brake mech-

anism for stopping the carrier at the cashier's 55 elevated station. Fig. 13 is a detail view of one end of said braking mechanism and showing its position on the friction brake rod. Fig. 14 is a top plan view of the propelling mechanism at the salesman's station. Fig. 15 is a detail view of the track wire and 60 part of the propelling mechanism. Fig. 16 is a perspective view of part of the propelling mechanism at the salesman's station.

Like letters of reference refer to like parts 65 throughout the several views.

A and B are the usual vertical standards rigidly attached to the ceiling in any desired manner. Located on the lower end of the standard A is a suitable casting A' through the lower end of which is adapted to slide the 70 rod A² on the forward end of which is the catch A⁴ supported by the standard A⁵ adapted to roll upon the arm A⁶ held in its position by the brace A⁷ connected to the bracket A⁸ on the arm A⁶ at one end and at 75 the opposite end to the bracket A⁸ adjustably secured to the standard A. The catch A⁴ is kept in its forward position by the spring A³ which is adapted to yield under the impact of the carrier entering the salesman's station. The propelling cord B⁶ has one end C' connected to the bar C⁶ of the pulley frame C³ (Figs. 2 and 16) and extending upwardly passes over the pulley C² on the casting A' and down around the pulley B¹⁰ 80 in the pulley frame C³ and up and around the pulley B⁹ in the casting A' and then forward in contact with the spool A¹¹ of the bracket A¹⁰ and continuing passes around the spool pulley B⁴ in the bracket B² when it is 85 connected to the knob A¹³ of the chain B⁷, which chain at its opposite end has another knob A¹² to which a continuation of the propelling cord B⁶ is attached and passes around the spool B⁵ (Fig. 14) and then rearwardly in 90 contact with the spool A¹⁴ in the bracket A¹⁰, and continuing rearwardly passes over the pulley B¹¹ in the frame C³ and up and around the pulley C⁷ and 95 down having its end C⁸ connected to the bar C⁶ of the pulley frame C³. To the pulley frame C³ is connected the cord C⁴ having the usual operating handle C⁵. The chain B⁷ has a ring B⁸ located on the track wire C which ring is adapted to hold the chain B⁷ in 100 proper position to receive the incoming car- 105

rier and thereby be carried back to be in position for the next propulsion of the carrier. The knobs A¹² and A¹³ prevent the chain from being pulled around the spools B⁴ or B⁵; further said chain is of great utility in that it is of much greater life than cord which was formerly used at the point of contact with the incoming carrier.

The mechanism for raising and lowering the basket consists of the stirrup G having two side arms G' and the cross base G⁴ in which is cut a suitable groove G³ for a purpose hereinafter described. The upper ends G⁵ of the side arms G' are hollow so as to receive the lower knotted ends of a suitable cord G⁶ which extends upwardly around the pulleys G⁷ G⁸ in the pulley frame G¹³ and continuing upwardly passes over the pulleys G⁹ and G¹⁰ in the pulley frame G¹¹ carried by the arm G¹² which forms a part of the bracket A⁸. This cord G⁶ continues downwardly and is connected to a suitable counterweight G¹⁵ to which is connected a suitable operating cord G¹⁶. This counterweight G¹⁵ when a carrier has been despatched to the opposite end brings the stirrup up into the position shown in Fig. 2 in which position the springs G¹⁷ hold said stirrup sufficiently below the track wire C so that the stirrup will pass between the two bails and allow the carrier to engage the catch A⁴. The carrier (Fig. 6) consists of suitable frame E² in which are mounted the wheels E E' on the standards E³ and E⁴ respectively and having on one end 35 a pivoted catch E⁵ having a roll E⁶ which is adapted to engage the catch A⁴ at the salesman's station and normally hold it in engagement with said catch A⁴. This catch is of the usual construction common in store service systems and needs no further description except to say that when the handle C⁵ of the propelling mechanism is pulled downward, the chain B⁷ pulls the catch E⁵ upwardly into the position shown in dotted lines Fig. 6 thus removing the roll E⁶ from the latch A⁴ and allowing the despatch of the carrier with the basket. This catch E⁵ is normally held in the position shown in full lines Fig. 6 so as to engage the catch A⁴ upon its entrance into the salesman's station and is held in the full line position by a spring (shown in dotted lines) around the shaft e in a well known manner in store service systems.

55 Within the frame of the carrier is located a suitable lock H Fig. 4 mounted on the fixed shaft H², and around said shaft is wound the wire H', the lower end of which extends downwardly and bears against the outside of the carrier frame (Fig. 4) while the upper end extends upwardly and over the pin H⁷ (Fig. 8) thus acting to hold the lock H under spring tension in the position shown in Fig. 4. Within the lock H is mounted the finger H⁴ on the fixed shaft H⁵ and around said shaft is

a spring H⁶, one end of which passes under the pin H⁷ and the other end is suitably secured in the upper end of the finger H⁴ and in the position shown in Fig. 4 holds the finger H⁴ against the under side of the carrier frame.

The basket F is provided with bails F' which are secured to the plate F¹² (Fig. 7) and said plate is provided with notches F² F³ to receive the side arms G' of the stirrup G when the carrier is at the salesman's station, and also with the notches F⁴ with which are adapted to engage the guides G² on the side arms G' of said stirrup, so that the plate F¹² will be properly located upon the stirrup G in raising and lowering. On the pin F⁶ supported in the brackets F⁵ F⁷ are located a center roll F⁹ and end rolls F¹⁰ F¹¹, and with the center roll F⁹ the recess H¹⁰ engages when the basket is locked to the carrier, and the rolls F¹⁰ F¹¹ reduce the friction as the basket is moved up and into position for engagement with the carrier.

Now when a carrier enters the salesman's station, the arms G' of the stirrup G enter the notches F² F³ and to detach the basket and lower the same, the operator takes hold of a suitable handle on the elevating and lowering cord G¹⁶ and pulling down on same will raise the stirrup so that the finger H⁴ will enter the groove G³ of the cross piece G⁴ of said stirrup and a continued pull will cause said finger to raise the upper end of the lock H so that it will pass up and away from the roller F⁹ when the basket will rest on the stirrup and can be lowered and the lock H returns to the position shown in Fig. 4. Now when the next parcel is to be sent, the salesman taking hold of a suitable handle on the elevating cord G¹⁶ will raise the basket which is on the stirrup with the guides G² in the notches F⁴ and raising same until the roller F⁹ strikes the lower side of the lock H, a continued pull will raise the lock against the tension of the spring H' until it is sufficiently raised so that the roller F⁹ upon a continued pull, will pass into the groove seat H¹⁰ between the points H⁸ and H⁹ and be held firmly to the carrier for despatch; upon the return of the carrier after being sent to the other end of the line, the operation takes place as previously described.

When a carrier is at the end of the line with the basket detached, it is necessary to have some device to prevent an accidental despatch of the carrier without its basket, and in order to accomplish this result there is provided a carrier-retaining device k' pivoted on the carrier frame at k⁴ and having the lower end k² and the upper end k³. When the basket is locked to the carrier as shown in Fig. 6, the end H¹¹ of the lock H tilts downward the end k² and raises the end k³ into the position shown in Fig. 6, so that the catch E⁵ can be operated to raise the roll E⁶ from the catch A⁴ to despatch the carrier. When

however, the basket has been detached from the carrier, the weighted end k^3 drops downwardly until it engages the notch k in the latch E^5 so that the chain B^7 pulling on the catch E^5 cannot raise the same, as the end k^3 locks the catch E^5 against movement and consequently the roll E^6 remains in engagement with the catch A^4 .

At the cashier's elevated station, the propelling mechanism is of ordinary construction and will be briefly described. On the lower end of the standard B is supported the cross pipe D^4 to which is clamped the casting D^3 and to said casting near the lower end 5 is pivotally secured at D^9 the bracket D^{10} which is adapted to support the rod D^5 extending outwardly and secured to the bracket D^6 which is supported and carried by the arm D^7 suitably secured to the pulley 10 casing D^8 on the casing D^3 . At D^{10} is pivotally secured the arm D^2 to the forward end of which is secured the wedge-shaped brake rod D' through which the wire way C passes and is suitably secured to the bracket B . 15 The propelling cords K^6 pass around the pulleys K^7 and are connected by the chain B^7 which is adapted to engage the carrier and propel the same when returning to the salesman's station. These cords are connected 20 at K^{10} and form one cord K^{11} which extends over the pulley K^5 in the pulley casing D^8 down and around the pulley K^3 and up and over the pulley K^2 terminating in the handle K' . The pulley K^3 is mounted in a suitable 25 frame and when the handle K' is pulled downwardly the springs K^8 on the opposite rods K^9 are compressed and after a carrier has been despatched, these springs move the pulley K^3 and its frame downwardly and 30 raise the handle K into a position up out of the way leaving the parts in the position shown at the left hand of Fig. 1.

The felt pads A^{10} and D prevent wear on the carrier wheels and counteract the strain 35 occasioned by locking and unlocking the basket at the salesman's station thereby relieving the wire of this additional work and avoiding the bending of the wire in both directions; it is well known that wire will last 40 much longer if always bent in the same direction.

At the cashier's station, the stop for the carrier is an elongated wedge D' over which the wheels pass, and the under side of the 45 wedge engages the brake shoe E^9 pivoted at E^8 having the roll E^{12} on its end, and the friction applied by the brake shoe may be increased or diminished by adjusting the spring E^{10} by the screw E^{11} . In the opposite end of 50 the carrier there is an arm E^{13} pivoted at E^{14} and carrying on its arm the roll E^{15} . In giving the carrier at the salesman's station a strong impulse to propel it, there is a tendency in the rear end of the carrier to lift 55 itself, and this roll is provided to prevent the

carrier from lifting beyond the line of the wire, so that the wire comes in contact with the roll which is simply used as an idler.

The spools A^{11} , A^{14} , B^4 , B^5 , allow the propelling cord to follow any depression in the wire, thus maintaining a direct forward motion to the propelling cord under varying loads. It will be understood that the spools must be set or adjusted to a point where the propelling cord will pay off at their upper 70 ends with the empty basket and as the load may be increased, the wires sagging as the result of said increased weight, the propelling cord will follow and pay off at a point on the spools in strict accordance with the amount 75 of weight in the basket until the limit of the weight has been reached, which it is assumed would be the maximum weight. The arrangement of the propelling cord gives the action of a bow spring giving the propelling 80 cord about twenty-four times the velocity of the hand during the last inch, this high speed of the cord beginning with three to one due to the block and pulley mechanism; the hand as above stated with a velocity ratio of 85 90 twenty-four to one would give the carrier a gentle but rapid impulse in the direction of its travel.

I do not limit myself to the arrangement and construction shown as the same may be 95 varied without departing from the spirit of my invention.

Having thus described the nature of my invention and set forth a construction embodying the same, what I claim as new and 100 desire to secure by Letters Patent of the United States is

1. In a store service apparatus, a carrier, a detachable receptacle provided with a suspending locking plate, locking mechanism 105 consisting of an arm adapted to be engaged by said suspending plate and to hold said receptacle in locking engagement with the carrier, a stirrup for raising and lowering said receptacle to bring said locking plate into 110 contact with said locking arm, and a releasing finger located on said arm and adapted to lie in the path of movement of the stirrup when the parts are in a locked position and out of said path when the parts are in un- 115 locked position whereby the movement of the stirrup may serve to release the receptacle or to lock the same to the carrier.

2. In a store service apparatus, a carrier, a detachable receptacle provided with a suspending locking plate, locking mechanism 120 consisting of an arm adapted to be engaged by said suspending plate and to hold said receptacle in locking engagement with the carrier, a stirrup for raising and lowering said receptacle to bring said locking plate into contact with said locking arm, and a spring-controlled releasing finger located on said arm and adapted to lie in the path of movement of the stirrup when the parts are in a 125 130

locked position and out of said path when the parts are in unlocked position whereby the movement of the stirrup may serve to release the receptacle or to lock the same to the carrier.

3. In a store service apparatus, a carrier, a detachable receptacle provided with a suspending locking plate, locking mechanism consisting of a spring controlled arm adapted 10 to be engaged by said suspending plate and to hold said receptacle in locking engagement with the carrier, a stirrup for raising and lowering said receptacle to bring said plate into contact with said locking arm, 15 and a releasing finger located on said arm and adapted to lie in the path of movement of the stirrup when the parts are in a locked position and out of said path when the parts are in unlocked position whereby the movement of 20 the stirrup may serve to release the receptacle or to lock the same to the carrier.

4. In a store service apparatus, a carrier, a detachable receptacle provided with a suspending locking plate, locking mechanism 25 consisting of a spring-controlled arm adapted to be engaged by said suspending plate and to hold said receptacle in locking engagement with the carrier, a stirrup for raising and lowering said receptacle to bring said 30 locking plate into contact with said locking arm, and a spring-controlled releasing finger located on said arm and adapted to lie in the path of movement of the stirrup when the parts are in a locked position and out of said 35 path when the parts are in unlocked position whereby the movement of the stirrup may serve to release the receptacle or to lock the same to the carrier.

5. In a store service apparatus, a carrier, a 40 detachable receptacle provided with a suspending locking plate, locking mechanism consisting of an arm adapted to be engaged by said suspending plate and to hold said receptacle in locking engagement with the carrier, a stirrup for raising and lowering said 45 receptacle to bring said locking plate into contact with said locking arm, a releasing finger located on said arm and adapted to lie in the path of movement of the stirrup when the parts are in a locked position and 50

out of said path when the parts are in unlocked position, whereby the movement of the stirrup may serve to release the receptacle or to lock the same to the carrier, and means for preventing the despatch of the 55 carrier until the basket is locked thereto, and adapted to be operated to allow the despatch of the carrier upon the locking of the receptacle to the carrier.

6. In a store service apparatus, a carrier, a 60 detachable receptacle provided with a suspending locking plate, locking mechanism consisting of an arm adapted to be engaged by said suspending plate and to hold said receptacle in locking engagement with the carrier, a stirrup for raising and lowering said 65 receptacle to bring said locking plate into contact with said locking arm, a releasing finger located on said arm and adapted to lie in the path of movement of the stirrup when 70 the parts are in a locked position and out of said path when the parts are in unlocked position, whereby the movement of the stirrup may serve to release the receptacle or to 75 lock the same to the carrier, and means for preventing the despatch of the carrier until the basket is locked thereto and adapted to be operated by said locking arm to allow the despatch of the carrier upon the locking of the receptacle to the carrier. 80

7. In a store service apparatus, a way, a carrier adapted to travel on said way, a propelling cord, a chain secured to said propelling cord and with which the carrier engages, and a ring free on said way and secured to 85 said chain and adapted to slide upon said way.

8. In a store service apparatus, a way, a carrier adapted to travel on said way, a propelling cord, and spools with which said propelling cord engages and adapted to allow a 90 vertical movement thereon.

In testimony whereof, I have signed my name to this specification in the presence of two subscribing witnesses, this 24th day of 95 December, A. D. 1904.

CHARLES W. McCORMICK.
